The ornamental design for a centripetal air/oil separator for pressurized wet sump oiling systems, as shown and described.

DESCRIPTION

FIG. 1 is a perspective view of a centripetal air/oil separator for pressurized wet sump oiling systems, showing my new design in an assembled configuration;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a perspective view thereof, illustrated with two port attachment blocks omitted for clarity of illustration; and,

FIG. 9 is an exploded perspective view of FIG. 8.

The broken lines shown in the drawings are for the purpose of illustrating portions of the article that form no part of the claimed design.
